UNITED STATES PATENT OFFICE.

JOHN McNAY RIMINGTON, OF 4 PICTON PLACE, NEWCASTLE-UPON-TYNE,
COUNTY OF NORTHUMBERLAND, ENGLAND.

WRITING OR BLOTTING PAD.

SPECIFICATION forming part of Letters Patent No. 355,209, dated December 28, 1886.

Application filed June 15, 1885. Serial No. 168,693. (Model.)

To all whom it may concern:

Be it known that I, JOHN McNAY RIMINGTON, of 4 Picton Place, Newcastle-on-Tyne, England, merchant, a subject of the Queen of 5 Great Britain, have invented new and useful Improvements in the Manufacture of Writing or Blotting Pads, of which the following is a specification, reference being had to the accompanying drawings.

10 This invention consists in a novel blotting-pad, hereinafter described and claimed.

The center part I build up out of a number of leaves of blotting-paper to a thickness of three-eighths of an inch, more or less. This 15 center part occupies the greater portion of the complete pad, and would be about fourteen inches long by twelve inches wide (more or less). On the right-hand side of the center blotting part I fix a number of leaves of writing-paper corresponding in thickness to the 20 number of leaves of blotting-paper. These leaves can be ruled or left plain. At the top of each leaf I print the word "Engagements," or other similar significant term. On the left-hand side of the central blotting part I fix a number of leaves of writing-paper, forming a 25 complete diary, commencing 1st of January and terminating the 31st of December. This diary I provide with a stiff cover of card-board or other suitable substance. This cover can 30 be utilized for advertising purposes without in any way interfering with the daily use of the said diary. On the left-hand side of central blotting part, immediately over the diary, I 35 fix a number of leaves forming date-slips, each leaf being dated for one week. The person using the blotter can always tell the day of the month by simply drawing a pen or pencil across each day as it passes and tearing off the slips 40 or leaf at the end of the week. I form a recess at the top edge of central blotting part, also at the top edge of engagement-slip and date-slip. This recess is to facilitate the removal of the leaves by the finger.

45 The accompanying drawings will more fully explain my invention.

Similar letters refer to similar parts throughout the several views.

Figure 1 is a view of the complete pad with 50 diary closed. Fig. 2 is a view of the complete pad with diary open. Fig. 3 is a view of the

complete pad, showing the diary open and one of the leaves of blotting-paper in the diary partly turned over, also one of the blotting-paper leaves of central blotting-pad loosened ready to remove or tear off, also one of the engagement-slips partly removed. Fig. 4 is a plan of Fig. 3 in the direction of the arrow.

A, Figs. 1, 2, 3, 4, is the central blotting part. 55
B, Figs. 1, 2, 3, 4, are the engagement-slips. 60
C, Figs. 1, 2, 3, 4, are loops to receive a pencil.
D is a suitable pencil passed into the loops C.
E, Fig. 1, represents the diary closed.
F, Figs. 2, 3, 4, represents the diary open.
G, Figs. 3 and 4, represents one of the leaves 65 of blotting-paper in the diary partly turned over, such leaf being interposed between the leaves F of the diary.

H, Figs. 3, 4, represents one of the leaves of the central blotting-pad loosened ready to remove or tear off. 70

J, Figs. 3, 4, represents one of the engagement-slips partly removed ready to tear off. The top part, K, of each sheet of the central blotting-pad can be used for advertising purposes in a similar manner to the stiff cover of diary. The leaves of the diary are not intended to be ripped out; but when the said diary is open ready for use it will be level with the blotting and engagement parts, as clearly 75 shown at Fig. 3.

L, Fig. 4, represents the back of mill-board or other suitable material, to which is fixed the various parts constituting my improved pad. 85

M, Figs. 1, 2, 3, 4, represents the recesses formed to conveniently fit the tip of finger when removing the leaves, as hereinbefore described. I can, where desirable, make these recesses parallel; or, where preferred, they can be made 90 to taper either with the small side at the top or at the bottom.

I am fully aware that the making of a blotting-pad formed of several layers of material is not new or original; neither is the making 95 of a diary or the binding of a number of engagement-slips together new or original when done separately; but what I consider to constitute the originality and novelty of my invention is the convenient arrangement of the 100 various parts to form one complete writing or blotting pad.

Having now fully described the nature of my invention and the manner in which the same is to be carried out, I declare that what

I claim is—

5 As an article of manufacture, a blotting-pad consisting of a card-board or similar backing, a central body of blotting-paper, an attached series of superposed sheets of writing-paper, and an attached diary, substantially as described.

In testimony whereof I have hereunto signed my name in the presence of two subscribing witnesses.

J. McNAY RIMINGTON.
